UNITED STATES PATENT OFFICE.

GURDON H. WILLIAMS, OF SOUTH BROOKLYN, OHIO, ASSIGNOR, BY MESNE ASSIGNMENTS, TO THE BROWN HOISTING MACHINERY COMPANY, OF CLEVELAND, OHIO, A CORPORATION OF DELAWARE.

BUCKET.

SPECIFICATION forming part of Letters Patent No. 747,818, dated December 22, 1903.

Application filed April 11, 1903; Serial No. 152,194. (No model.)

To all whom it may concern:

Be it known that I, GURDON H. WILLIAMS, a citizen of the United States, and a resident of South Brooklyn, county of Cuyahoga, and 5 State of Ohio, have invented a new and useful Improvement in Buckets, of which the following is a specification, the principle of the invention being herein explained and the best mode in which I have contemplated applying that principle, so as to distinguish it 10 from other inventions.

My invention relates to that class of devices commonly referred to as "clam-shell buckets," its object being to provide a structure of such 15 character as will be particularly adapted to the handling of the lighter mineral products, such as coal, in contradistinction from the heavier, such as iron ore.

Said invention consists of means hereinafter fully described, and particularly set forth 20 in the claims.

The annexed drawings and the following description set forth in detail certain mechanism embodying the invention, such description 25 closed means constituting but one of various mechanical forms in which the principle of the invention may be used.

In said annexed drawings, Figure I represents a side elevational view of a clam-shell 30 bucket embodying my invention in its open position, and Fig. II represents a similar view of such bucket in its closed position. Fig. III represents a horizontal sectional view taken upon the plane indicated by line 3 3, 35 Fig. I; and Fig. IV represents a vertical sectional view taken upon the plane indicated by line 4 4, Fig. II.

The frame of the device consists of two side plates $a a$ and a top plate a' , said side plates 40 being braced and separated by two rigid transverse bars $a^2 a^2$. From these bars depend four oscillatory arms $B B$, two from each bar, whose lower or free ends pivotally support the front or inner ends of two scoop members $C C$, connection being made by means of transverse bars $c c$, secured to each such member, as shown in Fig. IV. Each such scoop member has its front end provided with two laterally-disposed 45 or upright extensions $c' c'$, Figs. I and II, to the

lower portions of which are secured the aforementioned bars $c c$. These bars are disposed so as to cause the vertical planes containing their axes to fall within the vertical planes containing the axes of oscillation of arms B when the scoop members are in their closed position, as shown in Fig. II. The upper extremities of the extensions $c' c'$ are pivotally mounted by means of pivot-bolts $c^2 c^2$ upon two rigid links D , which are carried by and secured to a transverse bar E . Upon this bar E is rotatively mounted a grooved power-wheel F , to the periphery of which is secured one end of a closing-cable G . This cable is guided by a sheave g , suitably secured to the upper portion of the frame, a suitable aperture a^5 being formed in the top plate to permit the cable to properly pass through. Upon each side of the power-wheel coaxial with the rod and fixed relatively to said wheel is a conical drum $H H$, to the periphery of each of which is secured one end of a chain $h h$. These chains are wound upon the drums in a direction opposite to that of the winding of cable G upon wheel F . The other ends of such chains are secured to an equalizing-bar J , oscillatory mounted upon a rod j , secured to and between two standards $a^4 a^4$, mounted upon the top of the frame. These standards 70 rotatively support a sheave K , around which passes a lifting and lowering cable. 75

The outer side of each link D is formed or provided with a centrally-located guiding member d , which slides in vertical undercut grooves $a^4 a^4$, formed upon the inner surface of opposite sides, respectively, of the frame a , 80 these grooves being preferably provided by means of angle-bars $a^5 a^5$, riveted to said side plates, as shown in Fig. III.

It will be thus seen from the above-described construction that the power-wheel is 90 movable upwardly and downwardly—that is, it has an axis of rotation movable relatively to the frame—the oscillatory arm having axes fixed relatively to said frame and disposed laterally of the wheel-axis, and the scoop 95 members have axes of oscillation upon said arms, which axes are hence movable relatively to the frame and to each other, and

they also have a second set of axes in the links D, fixed relatively to each other, but movable relatively to the frame.

- When it is desired to open the bucket, 5 cable G is slackened away, thus permitting chains h h to unwind and the bucket to open, the upper ends of the extensions dropping downwardly with the wheel F, the scoop members assuming the position shown in Fig. I. 10 To close the bucket, the opposite movement is effected by pulling up upon cable G and winding up the chains h h. During such operation the guiding members d slide upwardly and downwardly in grooves a⁴ a⁴ and impart 15 to the axes of the pivot-bolts c² c² planes of movement fixed relatively to the frame, so that swaying of the scoop members relatively to the frame is prevented at all times.

The lower ends of the oscillatory arms being supported at the front or inner end of the scoop members and the vertical planes containing the axes of bars c c and axes of oscillation of arms B being located as described permit them to swing through an arc having 25 a larger horizontal base for a given width of frame than is the case when such support is effected at the rear or outer end of the scoop members. A maximum spread is hence attained for a given width of frame.

30 Other modes of applying the principle of my invention may be employed instead of the one explained, change being made as regards the mechanism herein disclosed, provided the means stated by any one of the following 35 claims or the equivalent of such stated means be employed.

I therefore particularly point out and distinctly claim as my invention—

1. In a clam-shell bucket, the combination 40 with two scoop members, of a frame, each such member having an axis of oscillation movable and an axis of oscillation fixed relatively to such frame, such movable axes being located near the front or inner ends of their 45 respective scoop members.

2. In a clam-shell bucket, the combination 40 with two scoop members, of a frame, each such member having an axis of oscillation fixed relatively to said frame, and two axes of oscillation movable relatively thereto, said latter two axes intersecting the front or inner portion of their respective scoop members.

3. In a clam-shell bucket, the combination with a frame, of two scoop members each provided at its front or inner end with an extension and having an axis of oscillation fixed relatively to said frame and two axes of oscillation movable relatively thereto, one of said latter intersecting said extension and the other being located near the front or inner portion of the respective scoop members. 55

4. In a clam-shell bucket, the combination with a frame, of two scoop members each having an axis of oscillation fixed and an axis of oscillation movable relatively to said frame, 65 the latter axes being fixed relatively to their respective scoop members, the vertical planes containing said latter axes being included between the vertical planes containing the frame-axes, when the said scoop members are 70 in their closed positions.

5. In a clam-shell bucket, the combination with a frame, of two scoop members each having an axis of oscillation fixed and two axes of oscillation movable relatively to said frame, 75 one of such movable axes having a plane of movement fixed relatively to said frame.

6. In a clam-shell bucket, the combination of a frame, two scoop members provided at their front or inner portions with extensions, 80 oscillatory arms connecting the said portions with said frame, and sliding members, said frame being provided with guides for the latter, and said extensions being pivoted upon said sliding members. 85

7. In a clam-shell bucket, the combination of a frame, two scoop members provided with extensions at their front or inner portions, oscillatory arms having one end mounted upon fixed pivots secured to the frame and 90 the other end pivotally secured to the front or inner portions of the scoop members, the end portions of such extensions having a fixed path of movement relatively to said frame, the fixed pivotal axes of said arms being located from each other a distance greater than 95 the movable pivotal axes when the scoop members are in their closed positions.

Signed by me this 9th day of March, 1903.

GURDON H. WILLIAMS.
